UNITED STATES PATENT OFFICE

94,287

DESIGN FOR AN AUTOMOBILE

Edward Hall Taylor, Oak Park, Ill.

Application April 7, 1934, Serial No. 51,347

Term of patent 7 years

To all whom it may concern:

Be it known that I, Edward Hall Taylor, a citizen of the United States, residing at Oak Park, in the county of Cook and State of Illinois, have invented a new, original, and ornamental Design for an Automobile, of which the following is a specification, reference being had to the accompanying drawing, forming a part thereof.

In the drawing:

Figure 1 is a top plan view of my automobile;

Figure 2 is a side elevational view of the automobile; and

Figure 3 is a rear view of the automobile.

I claim:

The ornamental design for an automobile, as shown.

In witness whereof, I hereunto subscribe my name, this 3rd day of April, 1934.

EDWARD HALL TAYLOR.
